PILE-FABRIC SEWING MACHINE

George W. Wesson, Bridgeport, Conn., assignor to
The Singer Manufacturing Company, Eliza-
beth, N. J., a corporation of New Jersey

Application November 5, 1940, Serial No. 364,363

10 Claims. (Cl. 112—2)

This invention relates to sewing machines and has for an object to provide a sewing machine for use in neatly and securely finishing the raw edges of pile-fabrics, rugs and the like.

Another object of the invention is to provide a sewing machine with improved means for attaching a strip to the base of a rug or other pile-fabric so as to cleanly bury the attaching stitches in the fabric-pile.

With the above and other objects in view, as will hereinafter appear, the invention comprises the devices, combinations, and arrangements of parts hereinafter set forth, and illustrated in the accompanying drawings of a preferred embodiment of the invention, from which the several features of the invention and the advantages attained thereby will be readily understood by those skilled in the art.

Fig. 1 is a front side elevation, partly in vertical section, of a portion of the bracket-arm and work-support of a sewing machine containing the present improvement. Fig. 2 is an enlarged fragmentary vertical section, partly in front elevation, of the feeding elements and the work-support, with a work-margin disposed therebetween. Fig. 3 is a front end elevation of the bracket-arm and a portion of the work-support. Fig. 4 represents a perspective view of the throat-plate of the machine. Fig. 5 is an enlarged top plan of the presser-foot, feeding foot and throat-plate of the machine.

The sewing machine has the usual frame including a substantially horizontal work-supporting bed-plate 1, and a hollow bracket-arm 2 terminating in a head 3 overhanging the bed-plate. Suitably secured upon the bed-plate 1 is a throat-plate 4 disposed between side slide-plates 5 and 6.

Rotatably journaled in the bracket-arm 2 is a horizontally disposed main actuating shaft 7, one end of said shaft carrying a crank-disc 8 provided with a crank-pin 9. The crank-pin 9 is connected by a link 10 to a vertically disposed needle-bar 11 carrying at its lower end an eye-pointed needle 12. Any suitable looper or loop-taker mechanism (not shown) may be employed for cooperation with the needle 12 below the throat-plate 4 in the formation of stitches.

The needle-bar 11 is journaled for endwise reciprocation in a swinging frame 13, pivotally supported at the upper end thereof by a fulcrum-pin 14 secured in the bracket-arm head 3 by a set-screw 15. The fulcrum-pin 14 is disposed so that the pivotal axis of the frame 13 is substan-

tially parallel to the axis of rotation of the main shaft 7.

Also, journaled for endwise reciprocation in the swinging frame 13 is a vertically disposed feed-bar 16 carrying at its lower end a feeding-foot 17 having a serrated work-engaging face and provided with a needle-aperture 18. The upper end of the feed-bar 16 is connected by a link 19 to one arm of a bell-crank lever 20, of which the other arm is connected by a link 21 to a crank-arm 22 of a horizontally disposed feed rock-shaft 23. The rock-shaft 23 is journaled in bearing-lugs 24 extending from the rear side of the bracket-arm 2, and said rock-shaft carries another crank-arm 25 connected to one end of a pitman 26 having at its other end a strap embracing an eccentric 27 carried by the main shaft 7.

The bell-crank lever 20 is fulcrumed, as usual, upon a block 28 suitably secured to a vertically disposed presser-bar 29. The presser-bar 29 is journaled for endwise movement in the bracket-arm head 3 and is yieldingly depressed by the usual spring 30. Attached to the lower end of the presser-bar is the shank of a presser-foot 31 provided, within the width of the work-engaging portion thereof, with a rectangular slot 32 affording clearance for the feeding-foot 17. The presser-foot 31 is therefore divided by the slot 32 therein to provide laterally spaced work-engaging portions disposed at opposite sides of the feeding-foot 17, and the work-engaging faces of said presser-foot portions are preferably serrated.

The throat-plate 4 is recessed in the upper face thereof and is provided within the recess with a needle-slot 33 elongated in the line of seam formation. Set into the throat-plate recess and secured therein by screws 34 is the base 35 of an upstanding work-supporting member in the form of a block 36 provided with a needle-slot 37 in vertical alignment with the slot 33 of the throat-plate. The block 36 has upwardly convergent opposed side walls terminating in a horizontally flat upper face 38 approximately equal in width to that of the feeding-foot 17 opposed to the block face 38. The block 36 is elongated in the line of seam formation, and the length of said block is preferably such as to support the feeding-foot 17 throughout the work-advancing movement thereof. The face 38 of the block is also opposed to the heel portion of the presser-foot 31, thereby limiting downward movement of the presser-foot.

Extending forwardly from the front end of the

block 36 is a prow 39, of which the upper face is substantially flush with the upper face 38 of the work-supporting block and is opposed by the toe of the presser-foot 31. The under face of the prow 39 is inclined upwardly from the block 36 toward the forward end of the prow, and the opposite side faces of the prow are convergently inclined forwardly, thereby forming a prow having a somewhat pointed free forward end spaced from the throat-plate 4, and having rearwardly divergent side walls terminating in the upwardly convergent side walls of the block 36.

The needle-bar frame 13 is operatively connected to a crank-arm 40 depending from a rock-shaft 41, disposed substantially parallel to the main shaft 7 and journaled in suitable bearings provided in the bracket-arm 2. The rock-shaft 41 is actuated by any usual or suitable mechanism and in timed relation to the reciprocatory movements of the needle 12 and the feeding-foot 17 to impart work-advancing and return movements to said needle and feeding foot.

It is a common practice in binding the raw edges of rugs and similar pile-articles to attach initially a binding tape *t* to the pile face along the marginal portion of the base material *r* of the rug. This initial operation is, for example, fully disclosed in the U. S. patent to W. J. Moran, No. 1,975,728, Oct. 2, 1934. Heretofore, the attached binding-tape has been then folded about the raw edge of the rug and blind-stitched to the under face of the rug base, the blind-stitching being effected by hand or by blind-stitching machines. The blind-stitching operation referred to is necessarily slow, and the binding tape is insecurely attached by the blind-stitches.

The present invention, as above described, provides for securely and neatly attaching the binding tape *t* to the under face of the rug-base *r*. The rug, with the tape attached to and folded about the raw edge thereof, is passed, pile-face down, over the work-supporting block 36 and under the presser-foot 31 and feeding-foot 17. The prow 39 functions to separate the depending pile *p* along the line of needle-penetration of the base-fabric *r*, and as the prow 39 is flush with the upper face 38 of the work-supporting block 36, the pile *p* is initially separated directly at the pile-face of the base-fabric *r*. The rearwardly divergent side walls of the prow 39 and the downwardly divergent walls of the work-supporting block 36 together function further to separate and to maintain separation of the pile *p* until after the stitches are set, thereby insuring that the stitches are cleanly buried between the pile-fibres and anchored against the pile-face of the fabric-base.

In the operation of the machine, the feeding-foot 17 descends until it engages the work. As the work is supported by the raised upper face 38 of the block 36 in the area of the work engaged by the feeding-foot 17, the work is free from buckling or crimping under the action of the feeding-foot, whereby the tape *t* may be properly attached. The needle 12 descends during the work-engaging movement of the feeding-foot 17 and, after penetrating the base fabric, passes downwardly through the work-supporting block 36 which maintains the pile separated. The needle 12 while in the work partakes of the work-advancing movement of the feeding foot 17 and then rises a substantial distance in advance of the rearward end of the work-supporting block 36, so that the stitches are set before the separated pile is free to resume its normal po-

sition. Consequently, the pile remains cleanly separated during the formation of the tape-attaching stitches. The presser-foot 31 is, of course, raised and lowered alternately with the feeding-foot 17 by means of the actuating connections therewith, above described and well understood in the art. The tape is thus securely attached to the base-fabric of the rug by stitches which are concealed on the pile face of the rug, and the operation may be performed with sufficient rapidity to substantially increase production as compared with the blind-stitching operation heretofore performed for the same purpose.

Having thus set forth the nature of the invention what I claim herein is:

1. In a pile-fabric sewing machine having stitch-forming and work-feeding mechanisms, a pile-dividing member having a substantially flat work-engaging face tapered at its forward end to form a pointed pile-dividing prow disposed in advance of said stitch-forming mechanism, the point of said prow being disposed substantially in the plane of the work-engaging face of said member for initially engaging and dividing the fabric-pile at the bases thereof to receive stitches therebetween.
2. A pile-fabric sewing machine having a bed-plate, stitch-forming mechanism including a reciprocatory needle, a work-supporting block rising from said bed-plate and having a substantially flat upper face provided with a needle-opening, said block extending lengthwise in the line of seam formation, work-feeding means opposed to the upper face of said block, and a prow extending forwardly from said work-supporting block lengthwise thereof, said prow having a pile-dividing pointed free end disposed substantially in the plane of said flat upper face of the block.
3. A pile-fabric sewing machine having a bed-plate, stitch-forming mechanism including a reciprocatory needle, a work-supporting block rising from said bed-plate and having a substantially flat upper face provided with a needle-opening, said block extending lengthwise in the line of seam formation, work-feeding means opposed to the upper face of said block, and a pile-dividing pointed prow extending forwardly from said work-supporting block lengthwise thereof and in spaced relation to said bed-plate, the point of said prow being disposed substantially in the plane of said flat upper face of the block.
4. A pile-fabric sewing machine having a bed-plate, stitch-forming mechanism including a reciprocatory needle, a work-supporting block rising from said bed-plate and having a substantially flat upper face provided with a needle-opening, said block extending lengthwise in the line of seam formation, work-feeding means opposed to the upper face of said block, and a pointed pile-dividing prow extending forwardly from said work-supporting block lengthwise thereof and in spaced relation to said bed-plate, said prow having rearwardly divergent side faces and having the upper portion thereof substantially flush with the upper face of said block.
5. A pile-fabric sewing machine having stitch-forming mechanism including a reciprocatory needle, a work-supporting block lengthwise extending in the line of seam formation, said block being provided with a needle-opening medially of the width of the block, means for feeding work lengthwise of said block, and a pile-dividing prow extending forwardly from said block and having a pointed free end disposed above the level of

the base of said block, said prow having rearwardly divergent opposed side walls and having its upper face terminating in substantially the upper face of the block.

6. A pile-fabric sewing machine having a bed-plate, stitch-forming mechanism including a reciprocating needle, a work-supporting block rising from said bed-plate and lengthwise extending in the line of seam formation, said block having downwardly divergent opposed side walls and being provided with a needle-aperture medianly of the width of the block, work-feeding means opposed to said block, and a pointed pile-dividing prow extending forwardly from said block lengthwise thereof.

7. A pile-fabric sewing machine having a bed-plate, stitch-forming mechanism including a reciprocating needle, a work-supporting block rising from said bed-plate and lengthwise extending in the line of seam formation, said block having a substantially flat upper face provided with a needle-aperture, and said block having opposed side walls downwardly divergent from said face, work-feeding means opposed to said block, and a pointed pile-dividing prow extending forwardly from said block lengthwise thereof, said prow having rearwardly divergent side walls and having the forward point thereof spaced from said bed-plate.

8. A pile-fabric sewing machine having a bed-plate, stitch-forming mechanism including a reciprocating needle, a work-supporting block rising from said bed-plate and lengthwise extending in the line of seam formation, said block having downwardly divergent opposed side walls and having a substantially flat upper face provided with a needle-aperture medianly of the width of the block, work-feeding means opposed to said

block, and a pointed pile-dividing prow extending forwardly from said block lengthwise thereof, said prow having rearwardly divergent side walls terminating in the divergent side walls of the block and having the point thereof disposed substantially in the plane of the upper face of said block.

9. A pile-fabric sewing machine having a bed-plate, stitch-forming mechanism including a reciprocating and laterally vibratory needle, means for reciprocating said needle, a work-supporting block rising from said bed-plate and lengthwise extending in the line of seam formation, said block being provided with a needle-opening medianly between the side walls of the block and elongated in the line of seam formation, a pile-dividing prow extending forwardly from said block, a feeding-foot opposed to the upper face of said block, and means for imparting work-advancing movements to said needle and feeding foot.

10. A pile-fabric sewing machine having stitch-forming mechanism including a reciprocating needle, a work-supporting block lengthwise extending in the line of seam formation, said block having a substantially flat upper face and being provided with a needle-opening medianly of the width of the block, a pile-dividing prow extending forwardly from said block and having rearwardly divergent opposed side walls, a presser-foot movable toward and from the upper face of said block, a feeding foot opposed to said block, means for imparting work-engaging movements alternately to said presser-foot and feeding foot, and means for imparting work-feeding movements to said feeding foot lengthwise of said block.

GEORGE W. WESSON.
